UNITED STATES PATENT OFFICE.

FRANK E. WELLMAN, OF KANSAS CITY, KANSAS.

APPARATUS FOR TREATING HYDROCARBON OILS.

Application filed March 20, 1923. Serial No. 626,386.

My invention relates to apparatus for cracking hydrocarbon oils, the present invention being somewhat in the nature of an improvement on my co-pending application 5 Serial No. 565,633, filed June 3, 1922, as to general type of apparatus and the method of heating. This application has matured into Patent No. 1,639,622, on Aug. 16, 1927.

- Among the objects of the invention are to 10 reduce the deposition of carbon on the still walls, to increase the amount of oil that can be treated in an apparatus of given content before it becomes necessary to shut down in order to clean out carbon deposits, and 15 to effect an economical improvement in the ratio of yield and quality of product. Other objects will appear from a perusal of the following specification and drawings accompanying the same.
- 20 In the drawings, which illustrate a preferred form of apparatus for carrying out my invention:

Fig. 1 is a vertical section through the center of the still taken on the line 1—1 of 25 Fig. 2 with the tubes back of the plane of the section omitted for the sake of clearness;

Fig. 2 is a top plan view of the apparatus; and

Fig. 3 is a transverse or horizontal section taken on the line 3—3 of Fig. 1.

Referring to the drawings in detail, 1 designates a cylindrical furnace or heating chamber in which is mounted a circular series of vertical cracking tubes 2 arranged 35 around the inside of the furnace wall and slightly spaced therefrom as shown in Figs. 1 and 3. The tubes are L-shaped with the bottom 3 of each tube projecting out through and beyond the furnace wall where it is 40 flanged and capped on the end as indicated at 4. The upper ends of the tubes 2 extend up through the furnace cover 5, and are capped as indicated at 6. Thus all the capped ends of the tubes are outside of the furnace. 45 To take vapor off from the oil while preventing the oil from foaming over into the vapor line, vaporizing drums 7 are provided around the top of the furnace, each of which is connected with several of the 50 cracking tubes 2 and a common vapor line 8, in the present embodiment, the sixteen cracking tubes being portioned among the four vaporizing drums in groups of four connected to the drums through pipes 9, see 55 Figs. 1 and 2.

Near the outer ends of the bottom portions 3 of the cracking tubes, connection is made outside the furnace between the cracking tubes and a manifold 10, extending around the furnace in the form of a split circle or 60 C with the ends 11 and 12 of the C-form closed or capped as indicated at 13 and 14. Outside circulating pipes 15 connect the vaporizing drums 7 below the liquid level, with manifold 10.

A pair of pipes 16 and 17 connect with the ends 11 and 12, respectively, of the manifold 10, which pipes function alternately as supply and residuum draw-off pipes. To enable this interchange of function to be effected both pipes are extended from the still to the desired point of discharge through block valves 18 and 19, and between these valves and the still both are connected through switching block valves 20 70 and 21 to the supply pipe 22. Thus with valves 21 and 18 closed, and 20 and 19 open, pipe 16 becomes the supply connection and pipe 17 the draw off, the rate of supply and draw off being controlled by valves 20 and 19, respectively. Obviously an interchange 75 of function between pipes 16 and 17 will be effected upon a reversal of the setting of the valves 18, 19, 20 and 21.

To enable a return distillate such as the 80 reflux from a fractionator, to be fed into the still along with the supply, a conducting pipe 23 for such return distillate is connected to both pipes 16 and 17 through suitable switching valves 24 and 25 between the 85 still and the valves 20 and 21.

Heat is imparted to the cracking tubes within the furnace by a rotating source of heat, in the form of a rotating burner 26, similar to those of my co-pending applications Serial No. 523,062, filed December 17, 1921 (Patent No. 1,576,563, March 16, 1926) and Serial No. 532,873, filed January 30, 1922 (Patent No. 1,581,896, April 20, 1926). In the present arrangement the burner 26 is 100 supplied with fuel and air through the fuel and air pipes 27 and 28 respectively, which together with the rotary member 29 of a swiveled coupling 30 and diaphragm 31 are rotated within the circular series of cracking tubes by means of the bevel gears 32 and driving pulley 33 connected with a suitable source of power, not shown. The bottom stationary part 34 of the swivel coupling is 105 supplied with fuel and air through the sta- 110

tionary lead-in pipes 35 and 36, provided with valves 37 and 38, respectively. For properly distributing the hot gases through the furnace and among the cracking tubes,

- 5 I provide a set of baffles 39 supported by a rod 40 hung from the furnace cover 5, while for producing the required draft through the furnace a stack 41 is provided, with which the upper portion of the furnace 10, chamber connects through pipe 42.

In the operation of the still to carry out the preferred cracking process, it is first charged, through one of the pair of pipes 16-17, for example, pipe 16 by way of supply pipe 22, valve 20, pipe 16 and manifold 10, to the working level as indicated at 43, which oil may or may not be warmed or preheated. The burner 26 is then put in operation and the oil in the cracking tubes 20 brought up to the desired cracking temperature. Vapors liberated from the oil in the vaporizing drums 7 are conducted off through the vapor line 8 to suitable fractionating, condensing and receiving devices,

25 not shown, but which may be of any known or other suitable type, while enough make-up is pumped in by way of the manifold 10 and pipe 16, to maintain the working level 43. After the make-up amounts to the

30 original charge the method of operation is changed. Residuum is now drawn off and the make up is pumped in fast enough to replace the oil drawn off in vapor form and as residuum. By governing these three fac-

35 tors that is, vapor drawn-off, residuum drawn off, and make up, we control our percentage. The vapor is continuously conducted off through the vapor line 8; while the level is maintained by drawing off the residuum from the end 12 of the manifold 10 by way of pipe 17, the amount drawn off being controlled by valve 19. Intermediate distillates such as the reflux from a fractionator, are returned to the still along with

40 the oil supply by way of the return distillate pipe 23, valve 24, pipe 16 and manifold 10. When the run is half over the flow of supply and residuum draw-off is reversed by reversing the setting of the valves, that is by closing valves 20, 24, and 19, and opening valves 21, 25 and 18.

The carbon deposit is thickest at the end where the residuum is drawn off and graduates down to nothing at the point where 55 charging is started. Thus by reversing the flow in the manner described a fairly even deposition of carbon on the different tubes is brought about, resulting in a delay of the necessity for a shut-down for cleaning.

60 In one reduction to practice of the present invention, in which the outfit comprised eight three inch tubes and eight four inch tubes with ten feet in the furnace, I have run sixty gallons an hour with very good results. In running this outfit, fifty barrels

are put through before shutting down for cleaning, with a yield of 40 per cent 60-61 gasoline based on the gas oil charged.

Having thus described my invention what I claim and desire to secure by Letters Patent is:

1. Apparatus for treating hydrocarbon oils comprising a retort and heating means therefor, means for taking off vapors from a point near the top of the retort, means for supplying oil to be treated and means for drawing off residuum both the latter means being at different points near the bottom of the retort, and means for reversing said points of supply and withdrawal. 80

2. Apparatus for treating hydrocarbon oils comprising a retort and means for heating the same, a drum member connected with the upper end of said retort, a circulating conduit extending from the drum to a point near the bottom of said retort beyond the influence of the heating means, means for drawing off vapors from a point above the upper junction of the drum and circulating conduit, and reversible means for feeding oil to the retort and for removing the residuum therefrom at separated points near the lower junction of the retort and circulating conduit. 90

3. Apparatus for cracking hydrocarbon oils comprising a furnace, a plurality of vertical cracking tubes arranged in a circle therein having their upper ends extending outside the furnace and their lower ends extending radially outside the furnace, a manifold extending around the outside of the furnace in the form of a split circle, manifold connections between said manifold and the lower outside ends of the cracking tubes, and means for feeding oil through said manifold to the cracking tubes whereby the direction of flow may be reversed at different times. 100

4. Apparatus for cracking hydrocarbon oil comprising a furnace, a plurality of vertical cracking tubes arranged in a circle 110 therein and terminating outside the furnace, a manifold connecting with the lower ends of said cracking tubes outside the furnace, means for interchangeably feeding oil to the several tubes through one end of the manifold and for drawing off residuum from the tubes through the other end of the manifold, circulating conduits arranged to conduct oil from the upper ends of the cracking tubes to the manifold, and means for taking off vapors at a point near the upper junction of the cracking tubes with the circulating conduits. 120

5. Apparatus for cracking hydrocarbon oils as claimed in claim 4 having vaporizing drums connected between groups of said cracking tubes and said circulating conduits, and means for drawing off vapors from said drums. 125

6. Apparatus for cracking hydrocarbon 130

oils as claimed in claim 3, in which the said feeding means are adapted to draw off residuum from the manifold from either end thereof.

- 5 7. Apparatus for treating hydrocarbon oils comprising a vertical shaft furnace open at the bottom for the influx of air and closed at the top with a flue vent thereat for products of combustion, combustion heating
- 10 means in the lower part of said shaft furnace, and a retort extending therethrough from the bottom to top, comprising a vertically arranged L-shaped cracking tube with its top end projecting through the top of the
- 15 furnace and its bottom projecting laterally through the side wall of the furnace, a vapor drum outside the top of the furnace connected to the upper end of said retort, a vertical circulating conduit outside the wall of the furnace connecting the upper end of the retort and said drum with the lower projecting L-shaped end of the retort, and means for feeding oil and for drawing off residuum from said retort and other means

for drawing off vapor from said vapor drum.

8. Apparatus as claimed in claim 7 with the additional features of means for directing the heat of combustion from the heating means in the lower part of the furnace shaft 30 against the vertical walls of the enclosed retort, as the products of combustion rise in the shaft.

9. The apparatus claimed in claim 7 with the additional features of a plurality of retort tubes arranged as described, combustion heating means arranged to direct heated products of combustion against all of said tubes, and baffling means in said furnace above the said combustion apparatus, shaped 40 and arranged to direct the products of combustion and heat currents laterally against the vertical walls of the retort tubes as said currents rise in the furnace.

In testimony whereof I hereunto affix my 45 signature.

FRANK E. WELLMAN.
